J. H. B. REA.

CHAIR SEAT.

APPLICATION FILED APR. 8, 1912.

1,047,447.

Patented Dec. 17, 1912.

UNITED STATES PATENT OFFICE.

JOHN H. B. REA, OF LA FAYETTE, GEORGIA.

CHAIR-SEAT.

1,047,447.

Specification of Letters Patent. Patented Dec. 17, 1912.

Application filed April 8, 1912. Serial No. 689,109.

To all whom it may concern:

Be it known that I, JOHN H. B. REA, a citizen of the United States, residing at La Fayette, in the county of Walker and State 5 of Georgia, have invented certain new and useful Improvements in Chair-Seats; and I do declare the following to be a full, clear, and exact description of the invention, such as will enable others skilled in the art to 10 which it appertains to make and use the same.

This invention relates to improvements in metal chair bottoms or seats.

The object of the invention is to provide a cheaply constructed, strong and efficient 15 metal chair bottom which adds materially to the strength and durability of the chair and forms a permanent bottom which will need no repairs during the life of the chair.

With this and other objects in view, the 20 invention consists of certain novel features of construction, and the combination and arrangement of parts as will be more fully described and claimed.

In the accompanying drawings: Figure 1 25 represents a side elevation of a portion of a chair equipped with this improved seat; Fig. 2 represents a horizontal section taken on line 2—2 of Fig. 1 looking in the direction of the arrows *a*; Fig. 3 is a similar view 30 on line 3—3 of Fig. 1 looking in the direction of arrow *b*; Fig. 4 is a detail vertical section taken on line 4—4 of Fig. 2; Fig. 5 is a similar view on line 5—5 of Fig. 2; Fig. 6 is a plan view of the blank from 35 which this improved bottom is formed.

In the embodiment illustrated, a plate 1 of sheet metal, preferably steel, is struck out in the form shown in Fig. 6, with the edges sloped or inclined toward their 40 centers, and the corners 2 thereof are folded over with their ends overlapping, as shown in Fig. 3.

A screw or bolt 3 is passed through the main body of the chair bottom and through 45 these overlapping corners and secured in any suitable manner, a nut being here shown applied to its lower end, and the head of the screw arranged flush with the outer face of the bottom forming the seat of the chair.

50 (See Fig. 4). By this construction a double walled chair seat or bottom is formed, the upper face or seat proper being formed by the body portion of the plate and the lower

wall or face being formed by the overlapping corners and spaced from the seat 55 proper a sufficient distance to receive between them the upper rungs B of the chair A. As shown, this seat is made square and the corners thereof cut out, as shown at 4, to provide recesses for engaging the chair 60 posts C, said recesses engaging the four posts of the chair which hold the bottom against lateral movement and the bottom spaces said posts and prevents collapse of the chair. While this bottom is shown 65 square, it is obvious that it may be made oblong, or of any other suitable or desired shape to fit the chair or other piece of furniture to which it is to be applied.

The blank shown in Fig. 1, is substantially square with the side edges sloped inwardly toward the center to provide for spaces between the adjacent edges of the corners when in folded position, as is shown clearly in Fig. 3. A plurality of apertures 75 5 are preferably formed in the bottom for ventilation. It is, of course, understood that this bottom may be painted or finished in any suitable or desired manner and when applied to a chair will reliably brace and 80 hold the parts thereof against collapse, the top and lower walls of said bottom adding greatly to its strength.

I claim as my invention:

1. A metal chair bottom composed of a 85 plate folded to form continuous upper and lower faces, and means for securing them together.

2. A chair bottom composed of an angular metal plate having the corners thereof 90 folded inwardly with their ends overlapping, and means for securing said overlapping ends together and to the body portion of the plate.

3. A chair bottom composed of a substantially square metal plate having its opposite corners folded inwardly with their ends overlapping, means for securing said ends together and to the body portion of the plate, said plate having recesses formed 100 therein between the corners of the plate to fit the chair posts.

4. A chair bottom composed of a substantially square metal plate having the side edges thereof curved inwardly and the opposite corners overlapped on the lower face 105

of the plate, said corners and body portion of the plate being provided with registering apertures, a bolt extending through said registering apertures for securing said members together to form a square double walled chair bottom, and recesses at the corners of said chair bottom.

In testimony whereof I have hereunto set my hand in presence of two subscribing witnesses.

JOHN H. B. REA.
